UNITED STATES PATENT OFFICE.

WILLIAM E. HASKELL, OF BRATTLEBORO, VERMONT, ASSIGNEE TO ESTEY ORGAN COMPANY, OF BRATTLEBORO, VERMONT, A CORPORATION OF VERMONT.

SPEAKING-PIPE.

1,327,996.

Specification of Letters Patent.

Patented Jan. 13, 1920.

Application filed June 17, 1919. Serial No. 304,817.

To all whom it may concern:

Be it known that I, WILLIAM E. HASKELL, a citizen of the United States, residing at Brattleboro, in the county of Windham and State of Vermont, have invented certain new and useful Improvements in Speaking-Pipes, of which the following is a specification.

This invention has for its object the construction of an open pipe to produce a more powerful tone than has been possible with pipes as heretofore made.

While this invention is primarily designed for organ pipes its peculiar qualities are such that it can be used for lighthouse and fog signaling as well. When used for an organ pipe it gives an open reed tone more closely similar to the tone of the cornet or tuba than has heretofore been obtained. With this pipe there seems to be no limit to the power of tone which can be produced, thus enabling it to be used for signaling purposes. The principles of the improved pipe will be understood from the specific pipe illustrated in the accompanying drawings, wherein—

Figure 1, is a front view of the pipe with portions broken away at the mouth thereof. Fig. 2, is a vertical longitudinal section on the line 2—2 in the Fig. 1. Fig. 3, is a top view. Fig. 4, is an enlarged vertical section of the pipe in the vicinity of its mouth. Fig. 5, is an enlarged front view of the pipe, the roller beard being removed. Fig. 6, is a detailed view illustrating the nicking on the interior of the mouth, on the line 6—6 of Fig. 2. Fig. 7, is a cross section in the plane indicated by the line 7—7 in Fig. 2. Figs. 8 and 9 are detailed cross sections in the planes indicated by the lines 8—8 and 9—9 in Fig. 4. Fig. 10, is a still larger section in the vicinity of the mouth of the pipe.

This pipe, as shown, is made of wood. The pipe A, has a face board B, a rear wall C, parallel side walls D, and an open top which, as shown in Fig. 3, is square. The front and rear walls are inclined with respect to each other so that the pipe increases in depth from the mouth E to the open top, as shown in Fig. 2. The face board or front wall B, is shorter than the rear wall C. The mouth E is equal in width to the interior width of the pipe. The rear wall C of this pipe is curved outwardly near the bottom

thereof toward the mouth E, as shown at 55 F in Fig. 2, thus forming a curved bottom or floor for the pipe which extends from the lower lip of the pipe and gradually merges into the rear interior upwardly extending surface of the pipe. In pipes heretofore constructed there has been a "dead" air space at the back of the pipe opposite the mouth, and accordingly, any condensation or rarefaction occurring at the mouth has been instantly dissipated thus at once losing 65 its intensity. In accordance with the present invention this dead space is eliminated by having the rear wall of the pipe curved outwardly toward the mouth thereby bringing this curve opposite the mouth. By this construction the maximum of condensation and rarefaction is imparted to the air column as the air reed bends in and out because the air passes in and out of this pipe more readily than with a pipe of any other shape. 70 This pipe has the additional advantage that there is a reflecting condition which tends to expel the sound wave as in a megaphone, while at the same time the sound wave formed at the mouth is primarily the width 75 of the mouth, and as the sides of the pipe are parallel, the sound wave is of the width 80 of the pipe clear to its top.

The block G (which, as shown, is in one piece of wood with the rear wall C), has a 85 transverse hole a therein connecting with the mouth of the foot b which in turn is connected with the wind-chest or compressed air supply, in the usual manner. The front of the block G is covered by a cap H which has 90 a throat c therein having at its upper end the deflecting surface d which directs the air on to a less abrupt surface e and thence through the wind-way f across the mouth E of the pipe. The wind-way f is of the same width as the 95 mouth E. Thus, any condition of condensation or rarefaction produced at the mouth of the pipe by the air reed will embrace the entire width of the air column at that point, being imparted to the column above it and 100 increasing in area according to the area of the pipe itself. The cap H has two upwardly extending ears g, one on each side of the wind-way, thereby providing a guide for the air reed as it comes from the throat 105 of the block G. In other words, the distance between these ears g is equal to the interior width of the pipe A. Between these

ears *g* is mounted the roller or draft bridge *I*. This bridge *I* is spaced away from the cap *H*, and the center of the bridge is substantially opposite the lower lip of the mouth, this location being such as to enable it to deflect the air reed back and forth and to provide the necessary induced current of air between the cap and bridge.

The upper lip *J* of the mouth *E* is beveled on both front and rear sides, as best seen in Fig. 4. The lower lip *K* is beveled on its front edge. Below the lower lip *K* the wind-way *f* is nicked as at *h*, in the customary manner, to prevent the hissing sound usually produced by a current of air under pressure passing a given opening.

The face 1 of the body of the pipe is in the same plane as the outer face 2 of the pipe above the upper lip, and the plane of the surface *e* of the inner part of the cap if extended upwardly would pass underneath the lip *J* and just inside of it as best seen in Fig. 10. These converging planes at the mouth *E* of the pipe tend to throw the sheet of air directly on the edge of the lip, while the bridge *I* is so placed that it provides a buffer for the reflection of the air reed as well as creating an induced draft between the bridge and the cap, which also tends to move in the same direction.

Wind is admitted through the foot *b* from a wind-chest, through the transverse passage *a* along the throat *c* and is directed out past the mouth *E* of the pipe in a sheet as wide as the column of air on the interior of the pipe. As the air reed strikes the exterior bevel of the upper lip *J* of the mouth *E* it is directed outwardly thus creating a vacuum. This causes a rarefaction within the pipe *A* and as the pressure within the pipe becomes less than the exterior pressure, the air reed is bent back within the pipe *A* causing condensation, the period of which, of course, is governed by the tonal length of the pipe. The curve *F* of the rear wall *C*, as well as the interior bevel of the upper lip of the mouth *E* and the smaller area of this pipe at its mouth greatly aid in this rarefaction and condensation. The amplitude of vibration reaches its maximum in the pipe of the present construction, and accordingly, the air reed is deflected well within the pipe, permitting a discharge of some of the air from the top of the pipe. The air reed being of the same width as the column of air within the pipe *A* the rarefaction and condensation produced at the mouth of the pipe affects the entire column of air within this pipe, increasing in volume as the area of the pipe increases.

If used with an organ the sizes of pipe are proportioned to the desired pitches of the several pipes. But with a pipe of the present construction, a tone is produced, which is expelled under the most approved condi-

tions to produce a more mellow and a more powerful tone than has heretofore been produced.

In making pipes of this character which are intended for signal purposes, proportions 70 can be employed which have this particular object in view. As an example of such a pipe one set of dimensions may be given which produce an efficient effect. Such a pipe with a speaking length of two feet will 75 be eight inches square at the top and proportionately tapered at the mouth. This pipe speaks on a pressure of fifty pounds and produces a tone as powerful as a steam whistle. In fact with a given area in proportion to its length, a pipe of this construction gives from ten to twenty-five times 80 as powerful a tone as any other pipe with which the present inventor is familiar.

I claim:

1. An open speaking pipe having, in combination, parallel side walls, front and rear walls at an angle to each other so that the interior of the pipe decreases in depth from top to bottom, being square at the top, with 90 a mouth at the lower end of the same width as the interior of the pipe, a curved bottom extending from the lower edge of the mouth rearwardly and upwardly and merging gradually into the inner face of the rear 95 wall, the upper lip of the mouth being beveled on both sides and the outer face of the lip being in the same plane as the body of the pipe below the lower lip, a cap at the lower end of the pipe having a throat and 100 wind-way of the same width as the mouth of the pipe, the inner face of the cap having a lower abruptly inclined face and above it a less abruptly inclined face, the plane of said upper inclined face constituting the 105 outer wall of the wind-way and being in a plane which if extended passes inside of the edge of the upper lip, said cap having upwardly extending ears extending above the top of the mouth and being spaced apart 110 a distance equal to the width of the mouth and of the interior of the pipe, and a roller bridge in front of the lower lip of the mouth with a free space between it and the portion 115 of the cap which constitutes the wind-way, and nicks on the part of the pipe beneath the lower lip of the mouth.

2. An open speaking pipe having, in combination, parallel side walls, front and rear walls at an angle to each other so that the 120 interior of the pipe decreases in depth from top to bottom, with a mouth at the lower end of the same width as the interior of the pipe, a curved bottom extending from the mouth rearwardly and upwardly and merging gradually into the inner face of the rear wall, the upper lip of the mouth being beveled on both sides and the outer face of the lip being in the same plane as the body of the pipe below the lower lip, a cap at the 125

85

130

- lower end of the pipe having a throat and wind-way of the same width as the mouth of the pipe, the inner face of the cap having an abruptly inclined face and a less abruptly inclined face, the plane of said less abruptly inclined face constituting the outer wall of the wind-way and being in a plane which if extended passes inside of the edge of the upper lip, said cap having ears extending above the mouth and being spaced apart a distance equal to the width of the mouth, and a roller bridge in front of the mouth with a free space between it and the portion of the cap which constitutes the wind-way.
3. An open speaking pipe having, in combination, side walls, front and rear walls at an angle to each other so that the interior of the pipe increases in depth from bottom to top, a mouth of the same width as the interior of the pipe, a curved bottom extending from the mouth and merging into the inner face of the rear wall, the upper lip of the mouth being beveled on both sides and the outer face of the lip being in the same plane as the body of the pipe below the lower lip, a cap at the lower end of the pipe having a wind-way of the same width as the mouth of the pipe, the inner face of the cap having an inclined face, the plane of which if extended passes inside of the edge of the upper lip, and ears maintaining a bridge in front of the lower lip of the mouth with a space between it and the portion of the cap which constitutes the wind-way.
4. An open speaking pipe of increasing depth from bottom to top, having a mouth at the lower end of the same width as the interior of the pipe, the upper lip of the
5. An open speaking pipe of decreasing depth from top to bottom having a mouth the upper lip thereof being beveled on both sides, a curved bottom which curves upwardly from the lower lip of the mouth toward the back of the pipe, a wind-way, and a bridge opposite the mouth.
6. An open speaking pipe of increasing depth from bottom to top having a mouth, the upper lip thereof being beveled on both sides, a curved bottom which curves upwardly from the lower lip of the mouth toward the back of the pipe, and a wind-way through which air is ejected across the mouth of the pipe.
7. An open speaking pipe of greater cross section at its top than at its bottom, having a mouth, the upper lip thereof being beveled, and the outer face of the pipe above the lip being in the same plane as the body of the pipe below the lower lip, and a wind-way the plane of the outer wall of which if extended would pass inside of the edge of the upper lip.
8. An open speaking labial pipe of greater cross section at its top than at its bottom having a mouth and a bottom which curves upwardly from the lower lip of the mouth toward the back of the pipe.

In witness whereof, I have hereunto signed my name.

WILLIAM E. HASKELL.
